FRANK A. PEARL, OF NORTH MILWAUKEE, WISCONSIN.

PERMANENT-WAVE CLIP.

Application filed November 5, 1926. Serial No. 146,482.

This invention relates to improvements in permanent wave clips.

In order to understand the purpose of the invention a brief explanation of the general practice in permanently waving hair will be given. The hair is wound on a number of bobbins, preferably winding a relatively few strands on each bobbin. A pad composed of loosely woven cloth containing moistened borax is next wrapped around the hair on each bobbin and the core thus formed is placed inside a paper tube. The upper end of the tube is closed by a wad and the lower end of the tube is crushed in and secured around the hair. Heat is next supplied to the tubes by electric heaters placed thereover and after the heating period, the heaters, tubes, and bobbins are removed. Various means have been employed for closing the lower end of the heating tube, and also insulating material has been inserted between the scalp and the tube to prevent blistering from escaping steam. It is also important that the tubes and heaters be arranged for very quick removal when desired so that the hair will not become too dry and brittle.

With the above in mind, therefore, it is the primary object of the present invention to provide a member for sealing the lower end of a heating tube which is self locking and which may be readily removed from the tube without pulling the hair.

A further object of the invention is to provide a clip of the class described which will serve to shield the scalp from heat radiating from the lower end of a heating tube and which will hold the tube at a comfortable angle.

A further object of the invention is to provide an adjustable and self locking clip of the class described which can be adjusted and unlocked very much more quickly than any of the devices and clips now in use.

A further object of the invention is to provide a permanent wave clip which is of very simple construction, is inexpensive to manufacture, is strong and durable, and is well adapted for the purposes described.

With the above and other objects in view the invention consists of the improved permanent wave clip and its parts and combinations as set forth in the claims and all equivalents thereof.

In the accompanying drawing in which the same reference characters indicate the same parts in all of the views:

Fig. 1 is a vertical sectional view of a heating tube shown in position over a bobbin and closed at its lower end by the improved clip;

Fig. 2 is a plan view of the clip, the tube and strands of hair engaged thereby being in section; and

Fig. 3 is a plan view of the clip showing the jaws spread apart.

Referring now more particularly to the drawing it will appear that the strands of hair, designated 5, are tied at the lower end 60 of a bobbin 6 and then wound tightly on the bobbin and tied to the upper end thereof. A cloth pad 7, suitably prepared, is then wrapped around the hair and a paper heating tube 8 is placed over the core thus 70 formed. The upper end of the tube is filled by a wad 9 and the lower end is completely sealed by means of the improved clip 10.

The clip 10 may be of any suitable material and is formed of a pair of arms or jaws 80 11 and 12 pivotally connected at 13. The free end portions of the jaws are twisted and flattened to form handle portions 14. Also, the outer edge portions of the jaws are formed with depending flanges 15 to elevate 85 the clip from the scalp. Extending inwardly medially from the inner edge of one of the jaws as 11 is a curved slot 16 provided with teeth or serrations 17 along one edge thereof. The other jaw 12 carries a depending pin 18 squared on the side adjacent the teeth and adapted to move in said slot 16 and yieldingly engage with any of the teeth 17 to releaseably hold the jaw 12 in adjusted closed position with relation to the 90 jaw 11. By means of the locking arrangement the clip may be adjusted to accommodate tubes of various sizes, which are received within the recessed portions 19 of the jaws.

The clip may be very quickly removed by merely forcing the handles 14 outwardly to open the jaws. Also, the clip is of very simple and novel construction and is well adapted for the purposes set forth.

What I claim as my invention is:

1. A permanent wave clip, comprising a pair of overlapping jaws hinged together at one pair of extremities and provided with releasable pin and tooth locking means 110

operable only upon lateral movement of the portion, and the other jaw having a fixed jaws, said pin and tooth being slightly flexible with respect to each other. 10

2. A permanent wave clip, comprising a pair of overlapping jaws pivotally secured together, one of said jaws being provided with a serrated slot inwardly of its edge

portion, and the other jaw having a fixed pin movable in said slot and engageable with the serrations. 10

In testimony whereof, I affix my signature.

FRANK A. PEARL.
